FINGER RING

Stanley Lawrence Sorrentino, Cumberland, R.I., assignor to Uncas Manufacturing Company, a corporation of Rhode Island

Filed June 9, 1960, Ser. No. 60,894

Term of patent 14 years

(Cl. D45—10)

F I G. 1

F I G. 2

F I G. 3

Fig. 1 is a front elevational view of a finger ring showing my new design;

Fig. 2 is a top plan view thereof; and

Fig. 3 is a side elevational view thereof.

I claim:

The ornamental design for a finger ring, substantially as shown.
